UNITED STATES PATENT OFFICE.

JOHN C. GUNDELFINGER, OF LINN, MISSOURI.

DEVICE FOR MAKING LEMONADE.

SPECIFICATION forming part of Letters Patent No. 599,605, dated February 22, 1898.

Application filed August 30, 1897. Serial No. 650,065. (No model.)

To all whom it may concern:

Be it known that I, JOHN C. GUNDELFINGER, a citizen of the United States, residing at Linn, in the county of Osage and State of Missouri, have invented certain new and useful Improvements in Devices for Making Lemonade, of which the following is a full, clear, and exact specification.

My invention seeks to provide a device by which ice may be crushed, lemons strained and squeezed, and the liquid mixed. This object is attained by the use of the device illustrated in the accompanying drawings; and the invention consists in certain novel features hereinafter described and claimed.

In the drawings referred to, Figure 1 is an elevation of the complete device. Fig. 2 is a vertical section of the can on line *xx* of Fig. 1. Fig. 3 is a detail view of the cover for the can. Fig. 4 is a detail view of the bottom of the can, and Fig. 5 is a detail plan view of the base-board.

The base-board A is formed with a groove or depression B in its upper surface to receive and hold the glass in which the liquid is dispensed. The board will usually be secured to a store-counter; but for family use it will be left free, so that it may be placed upon any convenient stand or support. Upon this base-board I secure the legs or standards C on the opposite sides of the groove B, and to the upper ends of these standards I secure the can D. This can D has an arm E rising from its upper end, and to the end of this arm I pivot a lever F. Pivoted to and depending from this lever is a plunger-rod G, having a crushing-disk H secured to its lower end. This disk H is of such a diameter as to fit closely within the can, and its convex side is provided with crushing teeth or projections I, as shown. At a point just about the lower limit of the stroke of this plunger I provide the concave strainer J, which is secured to a rock-shaft K, journaled in the sides of the can and having one end formed into an operating crank-arm L. Below the crusher and strainer is a rotary dasher or mixer consisting of a vertical shaft M, having its ends journaled, respectively, in the bottom of the can and a cross-bar N secured in the can, and wings or paddles O, secured to and radiating

from the said shaft. On the upper end of the shaft M is a gear-wheel P, meshing with a pinion Q on the inner end of a shaft R, journaled in the side of the can and extending 55 through the same. On the outer end of this shaft is a pinion S, meshing with a driving gear-wheel T, mounted on the side of the can and provided with a handle U. The bottom of the can is provided with a number of discharge-openings V, and pivoted centrally on the under side of the can-bottom is a damper or valve W, adapted to close said openings and having a handle X projecting to one side. Pivoted on a shoulder Y of the arm E are 60 the cover-sections a b, adapted to close around the plunger-rod G and close the top of the can. The sections are fastened by a hook c, pivoted on one section and engaging a staple d on the other section. 70

The manner of using the device will be readily understood. The valve in the lower end of the can being closed, a piece of ice is placed in the strainer and the crushing-disk then brought down forcibly on the same, 75 thereby breaking up the ice into small particles. The crank-arm L is then turned so as to invert the strainer and drop the ice to the bottom of the can. The strainer is then returned to its normal position and a piece of 80 lemon placed therein. The crushing-disk is then brought down slowly on the lemon, the juice being thereby squeezed therefrom and caused to pass through the strainer into the lower mixing portion of the can. Sugar is 85 then added and the handle U rapidly turned. The gearing will thus be set in motion and the dasher rotated, so that the several ingredients will be thoroughly mixed, after which the valve in the bottom of the can is opened 90 and the mixture discharged into a glass previously placed thereunder in the groove of the base-board.

It will be readily appreciated that the device is of a simple and compact construction 95 and that by its use lemonade may be rapidly and easily made. A cap may be placed over the gearing within the can to prevent the same being checked by the particles of ice or any lemon-seeds which may happen to drop from 100 the strainer.

Having thus described my invention, what

I claim, and desire to secure by Letters Patent, is—

1. The combination with the can, of a mixer in the lower portion thereof, a rock-shaft 5 mounted in the upper portion of the can, a strainer secured on the rock-shaft, and a crushing-disk above said strainer and adapted to coöperate therewith.
2. The improved device for making lemonade comprising a can having a perforated bottom, a valve pivoted on the bottom and adapted to cover the perforations therein, a

rotary dasher mounted on the bottom of the can, gearing mounted on the side of the can and connected with said dasher to rotate the 15 same, a rock-shaft mounted in the can above the dasher, a strainer secured on said rock-shaft, and a crushing-disk mounted above the strainer and adapted to coöperate therewith.

JOHN C. GUNDELINGER.
